ATTACHMENT FOR LOOMS

Filed Aug. 15, 1928

FIG. 2

Inventor
R. Pormann

By Attorney

Frank Ledermann

UNITED STATES PATENT OFFICE

ROBERT PORMANN, OF UNION CITY, NEW JERSEY

ATTACHMENT FOR LOOMS

Application filed August 15, 1928. Serial No. 299,662.

The main object of this invention is to provide an attachment for looms for the purpose of supporting the work on one side of the reed in a fashion which will permit its ready feeding to the looms.

The above and other objects will become apparent in the description below in which characters of reference refer to like-named parts in the drawing.

10 Referring briefly to the drawing, Figure 1 is a perspective view of the loom attachment showing a section of the reed mounted in place thereon.

15 Figure 2 is an end elevational view of Figure 1.

Referring in detail to the drawing, the numeral 10 indicates the right-hand bracket of the attachment. The numeral 11 indicates a bracket of similar outline and construction 20 which is mounted on the left-hand side of the attachment. These brackets are provided with ears in which elongated slots 12 are formed. The slots receive bolts which secure these brackets to the swards of a loom. Near 25 the lower ends of these brackets blocks 13 are secured. The blocks are mutually aligned with each other and are provided with oil cylinders 14. The stated blocks have openings therein into which the reduced ends 15 of a work supporting spindle 16 are rotatably mounted. The work supporting spindle 16 extends across the entire width of the lay and is circular in cross section and is adapted to roll with the work. As the spindle is relatively long it requires a support, at positions intermediate its length. The lower half of 30 the spindle is encased in a channeled beam 17. The channel in this beam is semi-circular in outline and of a larger dimension than the diameter of the spindle. Grooves, at spaced-apart positions in the beam, open into the channel. These grooves receive layers of felt 18. The beam is supported on a platform 19 which is attached to the lower ends 40 of the right-hand and left-hand brackets 10 and 11 respectively. This platform is of sufficient area to permit the construction of a ledge 20 at one of its longitudinal edges adjacent the beam 17 and, in the space 21, between the beam and the ledge, an upright loom reed 50

22 is erected and secured in place by a pack block 23. The reed consists of an upper and lower ridge 24 and 25 respectively, between which thin, mutually spaced-apart, parallel strips 26 are provided. The spaces between 55 these strips receive the warp threads of the work as they pass over the spindle 16.

The device is supported on the lay of a loom and is adapted to support, in turn, the work. Previously the work, as it passed over the lay, would not have a rolling surface for a support but had a rigid stationary surface and this, sometimes, would fray or fracture the threads of the work. It is the purpose of this invention to provide a rolling 60 support for the work in the form of a rotatable spindle mounted directly on the lay behind the reed 22 of the loom so that the warp strings as they pass through the spaces between the strips 26 of the reed will rest upon 70 the rotatable spindle 16 and, in being fed along to the support spindle, will rotate the spindle.

It is to be noted that certain changes in form and construction may be made without 75 departing from the spirit and scope of the invention.

I claim:

In a loom, a pair of spaced apart brackets adapted to be supported on the lay of the 80 loom, blocks mounted rigidly on said brackets, a spindle rotatably mounted in said blocks for supporting the warp strings being fed to the loom, a platform connecting said brackets and being attached to the latter, 85 a reed supported on said platform, a beam mounted on said platform, said beam having grooves traversing said channel, and a felt layer projecting from said grooves serving as a support for said spindle, said beam having a longitudinal channel therein receiving one-half the periphery of said spindle, said spindle resting upon said felt layer, said felt projecting above the channel surface. 90

In testimony whereof I affix my signature. 95
ROBERT PORMANN.
